ELECTRIC VIBRATOR

Harry L. Drake, Jr., 15925 Barbata Road,
La Mirada, Calif.

Filed Apr. 27, 1959, Ser. No. 55,670

Term of patent 14 years

(Cl. D83—1)

Fig. 1 is a side elevational view of an electric vibrator embodying my new design, the opposite side being substantially like the side shown;

Fig. 2 is a top plan view thereof;

Fig. 3 is a left end elevational view thereof, the vibrator head being omitted for convenience of illustration;

Fig. 4 is a section taken on line 4—4 of Fig. 1; and

Fig. 5 is a sectional view taken on line 5—5 of Fig. 1.

The dominant features of my design reside in the full line portions of the drawings.

I claim:

The ornamental design for an electric vibrator, as shown and described.
